VANITY

Joseph H. Fox, 735 Pelham Parkway, New York, N.Y.

Filed Aug. 17, 1959, Ser. No. 57,199

Term of patent 14 years

(Cl. D33—6)

Fig. 1 is a perspective view of the vanity;
Fig. 2 is a side view;
Fig. 3 is a top plan view of the same; and
Fig. 4 is a front view of the mirror and table of the vanity in separated relation.

The characteristic features of the new design are the oval table top, which is transparent to show through it the ornamental supporting grill, the oval mirror supported by ornamental scrolls at the back of the oval table, the reversely bowed legs with scrolls between the spaced members forming such legs and the oval shaped brace connecting the lower portions of the legs and matching the shape of the oval table top and forming a harmonious ensemble.

I claim:

The ornamental design for a vanity, substantially as shown and described.
